METALLIC MOLDING SECTION

Theodore W. Barton, Rutherford, N. J.

Application December 10, 1949, Serial No. 132,353

5 Claims. (Cl. 20—11)

1
My invention relates to improvements in construction elements and more particularly to a novel metal moulding or trim which may be advantageously used to finish off siding installations around window and door openings.

It has been found extremely desirable in the building trade to use insulated shake materials for sidings or outer walls in frame houses in place of the conventional wooden shingles or wooden boards. This shake siding is a rigid composition material which is usually made of pressed pulp wood, cane, or other fibrous material mixed with insulating material, and manufactured in the form of shingles or flat sheets. This type of siding has shown distinct advantages over wood both as to economy of manufacture, and as to durability in use.

Insulated shake siding may be used to provide the original outside walls of new frame houses, or it may be used in renovating or re-decorating the outside of old houses, the insulated siding in this instance being nailed over the original wooden siding.

There has, however, been considerable difficulty experienced in the installation of the aforementioned composition siding, since no method has as yet been found to trim the edges of the siding around window and door openings in order to provide a water-tight seal thereabout. The mouldings now used in this connection have been found to be manufactured with surfaces which are slightly uneven, so that the siding when applied would not firmly abut the moulding to provide the necessary water-tight seal. Mouldings of this sort, especially the conventional wooden moulding also have a tendency to warp once they have been applied, thus forming cracks between it and the siding edges. These same difficulties arise when the edges of the siding are not cut absolutely true or even, which is generally the case. These difficulties are due to the fact that conventional mouldings and trims are rigid and not resilient.

I provide metallic moulding sections which may be cut to fit about the top and sides of a window- and door opening and to act as a trim for said openings. The metallic sections are flexible in a transverse direction so that they will be held under their own spring tension firmly against the adjacent edges of the house siding, and will thus provide a water-tight seal with said siding. These moulding sections may be used as a universal trim in the application of any type of siding both in shingle or flat sheet form, although they were devised to be used especially with the insulated shake siding previously described. The moulding

2
sections may be used as a trim in the building of new houses, or it may be used in conjunction with the original moulding in order to provide a trim between said original moulding or trim and the new siding in the re-decoration of an old house.

The trim sections are adapted to be attached above a door or window opening in which position they serve not only as a trim, but are so constructed as to provide an adequate drip cap therefor.

The trim sections are made of thin sheets of non-corrosive metal so that in addition to being provided with the necessary resiliency, they present an attractive appearance in the finished house. The metal sections have an added advantage over the conventional wooden mouldings since they will not absorb the oil from caulking compounds, as wood is known to do. Therefore, in using my metal moulding sections, the caulked joint between the moulding sections and the siding will always remain water-tight and the caulking cannot dry out and shrink away from both sides as commonly occurs when a wooden moulding is used.

Other objects and advantages of the invention will be readily apparent in the course of the following specification when taken in connection with the accompanying drawings in which:

Fig. 1 is a perspective view of a moulding section made according to my invention;

Fig. 2 is a sectional view thereof, taken along line 2—2 of Fig. 1;

Fig. 3 is an elevational view of a portion of a house wall in which the moulding sections have been used to trim a window opening;

Fig. 4 is a transverse section taken along line 4—4 of Fig. 3;

Fig. 5 is an enlarged sectional view of the moulding section shown at the left of Fig. 4;

Fig. 6 is a sectional view similar to that of Fig. 4, but showing a different type of installation of the moulding section;

Fig. 7 is an enlarged sectional view of the trim section shown at the right of Fig. 6;

Fig. 8 is a vertical section taken along line 8—8 of Fig. 3;

Fig. 9 is an enlarged sectional view of the moulding section shown in Fig. 8.

Referring in detail to the drawings, and in particular to Figs. 1 and 2, I provide moulding sections designated generally as reference numeral 10. These sections 10 are made in single integral pieces, such as the piece shown in Fig. 1, preferably of a non-corrosive metallic material which

is thin and somewhat flexible. Aluminum, copper or zinc are preferred examples of such a metal, although suitable alloys and other well-known equivalents having the desired characteristics may be employed.

The moulding sections 10 are formed from strips or sheets of metal which are bent into the shape shown in Fig. 1. I have found it convenient and desirable to bend the sections by a series of rolling machine operations. I prefer to use metal strips or sheets of .018 inch gauge in order to obtain the necessary longitudinal rigidity of the bent moulding sections, while at the same time providing sufficient transverse flexibility. The sections 10 may be made in any desired lengths and cut to fit a particular installation.

Each moulding section 10 has a pair of parallel walls 11 and 12 which are joined at their top edges by an integral and transverse wall 13 which normally extends perpendicularly thereto. The walls 11, 12 and 13 thus form a main body portion of the moulding section which, as shown in Fig. 8 is U-shaped in cross-section. The outer wall 11 is slightly longer than the wall 10, preferably approximately $\frac{1}{8}$ inch longer, for a purpose which will be presently described. An integral nailing strip 14 extends laterally from the bottom edge of inner wall 12. This nailing strip 14 may be provided with a central longitudinal rib 15 which is provided to strengthen said strip 14 and to increase its rigidity and resistance from buckling. The outer wall 11 is formed with an inwardly-depressed longitudinal channel or slot 16 which serves an important function when the moulding section 10 is used in its drip-cap application. The slot 16 is preferably located adjacent the top end of said outer wall 11.

Because of the resilient nature of the moulding section 10, the walls 11 and 12 may be yieldably pressed toward each other, but the U-shaped construction tends to bias said walls 11 and 12 back to their normal parallel position.

While the moulding sections 10 may be formed in any desired relative dimensions, I find that the following dimensions are most desirable in providing a universal moulding or trim. Wall 11 is preferably $1\frac{1}{8}$ inches high; wall 12, $1\frac{1}{8}$ inches high; wall 13, $\frac{1}{4}$ inch wide, nailing strip 14, $\frac{3}{4}$ inch wide, and channel 16, $\frac{1}{8}$ inch deep and $\frac{1}{4}$ inch from the top of wall 11. Since insulated shake siding is generally 1 inch thick at the joint, while wooden siding is generally $1\frac{1}{8}$ inches thick at the joint, the moulding sections of the preferred dimensions may be readily used to trim both types of siding. The moulding sections will also project beyond or be flush with most standard wood mouldings or trims.

Figs. 3 through 9 disclose several ways in which the moulding sections 10 may be applied in use. Since their use is more varied in the application of the moulding sections to a house in which new siding is nailed over the original siding and the original trim is retained, the drawings will be limited to the use of the moulding sections in this connection. It is to be understood, however, that the moulding sections are equally adapted to be used as the only trim necessary to finish the application of siding around window and door openings when building a new house.

Fig. 3 shows the moulding sections 10 attached around the window opening W of an old house, which window opening W has the usual sill L and is already provided with a conventional moulding or trim M. For clarity of description, this conventional trim M will henceforth be described

throughout this specification as a "wooden trim." The moulding sections 10 have been inserted between the wooden trim M and the new insulated composition siding N, which has been nailed over the original siding S of the house. The original siding S is shown in Figs. 4 and 5 in the form of wooden shingles, while the insulated composition siding is shown as a flat sheet or board, by way of example only, it being understood that the moulding sections 10 may be used when new and old siding of any type is used. For convenience, the original siding S shown in Figs. 4 and 5 will be referred to as "wooden shingles" while the new insulated composition siding N will be hereinafter referred to as "composition siding."

The sectional view of Fig. 4 shows the inner construction of the house adjacent the window opening W. The inner edges of the window opening W are shown bordered by the usual window casing C. The casing C is secured to respective studs T of the house, as is the sheathing H and the inner wall I. The wooden shingles S are nailed to the outer surface of the sheathing H. The wooden trim is secured to the sheathing H and to the outer edge of the window casing C. The aforementioned house construction is conventional.

Figs. 4 and 5 show the application of the moulding sections 10 in what may be termed its "recessed application." In these views the wooden trim M is offset in relation to the wooden shingles S of the house, so that the outer edge of said wooden trim M projects beyond the outer surface of the wooden shingles S, forming a recessed portion at the abutting edges thereof into which the moulding sections 10 are inserted.

To attach one of the sections 10, the nailing strip 14 is fixedly secured to the wooden shingles S by a series of suitably spaced nails A at a position close enough to the wooden trim M to enable the outer wall 11 of the section to firmly abut the edge of said wooden trim M along its entire length. Due to the resilient nature of the moulding section 10, the U-shaped main body portion produces a spring effect which biases the outer wall 11 against the edge of the wooden trim M, and provides a tight seal between said outer wall 11 and said edge of the wooden trim M. Even if the edges of the wooden moulding M are slightly uneven or warped, the flexible metallic outer wall 11 will tend to compensate for such unevenness and make a tight seal along the entire surface.

In applying the composition siding N to the house, the edge of said siding N is firmly pressed against the inner wall 12 of the affixed moulding section 10, as shown in Fig. 5, and the composition siding N is nailed over the wooden shingles S of the house. The inner wall 12 is thus bent slightly inwardly, so that it exerts spring tension against the edge of the composition siding and makes a water-tight seal therewith. To further insure a water-tight seal, caulking material may be applied between the inner wall 12 and the composition siding N and between the outer wall 11 and the wooden moulding M.

The nailing strip 14 is thus concealed under the composition siding N, and the transverse wall 13 serves as the face of the moulding sections. It may thus be seen that the moulding sections 10 provide an attractive trim for the outer surface of the house. Since the sections 10 are made of a non-corrosive metal, they need not be painted, and will not deteriorate even in the most inclement weather.

Figs. 6 and 7 illustrate another application of the moulding sections 10 in a house which is similar to that previously described, except that the original siding D is in flat sheet form and is flush with the outer edge of the wooden trim M. This may be referred to as the "flush application" of the moulding sections 10. The nailing strip 14 of the moulding section 10 is firmly nailed to the face of the wooden trim M. I prefer to nail said moulding section 10 at such a position that the outer wall 11 is spaced approximately $\frac{1}{4}$ inch from the edge of said wooden trim M. Since the outer wall 11 is longer than the inner wall 12, the free longitudinal edge of said outer arm 11 will bite into the face of the wooden trim M, as shown in Fig. 7, making a tightly sealed joint therewith. The composition siding N is nailed over the original siding D and over a portion of the wooden trim M with the edge of said composition siding N pressing firmly against the inner wall 11 of the moulding section 10. The difference in length between the inner wall 12 and the outer wall 11 will also cause the transverse wall 13 to tip or incline toward the composition siding N, thus maintaining the tension between the inner wall 12 and the edge of the composition siding N, and insuring a tight joint therebetween. Caulking material may be applied between the nailing strip 14 and the wooden trim M, and between the inner wall 12 and the composition siding N in order to make the joints absolutely water-tight.

Figs. 8 and 9 illustrate the application of one of the moulding sections 10 as a drip-cap, the section 10 being installed as the top trim of the window W of Fig. 3. In these figures, the top of the window casing C is shown secured to the usual headers E of the house, to which is also secured the sheathing H and the inner wall I. The lower edge of the adjacent wooden shingle S of the original siding abuts the upper edge of the original wooden trim M. Since the wooden shingles S are not flush with the outer face of the wooden trim M, the moulding section 10 is attached in the same manner as was described for its "recessed application" of Figs. 4 and 5. The nailing strip 14 of the moulding section 10 is nailed to the wooden shingle S adjacent the top edge of the wooden trim M in such a position that the outer wall 11 is pressed against the edge of said wooden trim M. The composition siding N is then nailed to the wooden shingles S with the edge of said composition siding N pressing against the inner wall 12 of the moulding section 10. The body portion of the moulding section 10 is thus mounted in a horizontal position with the recessed channel 16 on the bottom face thereof.

In moderate or heavy rain, water flowing down the side of the house will flow over the projecting face of the moulding section 10, and will tend to flow back along the bottom surface of outer wall 11. The presence of the recessed channel 16, however, prevents this return flow, since said channel 16 presents a break in the surface of the outer wall 11, from which the flowing water will drip before it has travelled the width of said outer wall 11.

When three of the moulding sections 10 have been used to trim the top and sides of a window opening, as shown in Fig. 3, the edges of said moulding sections 10 may be mitered to present a compact and unbroken appearance to the trim.

In using the moulding sections 10 as the only trim around door and window openings in the construction of a new house, the identical pro-

cedure is used as in the case of the "flash application" of Figs. 6 and 7. Since the new house will not have a wooden trim or wooden shingle or board sidings, the moulding sections may be nailed directly to the window or door casing and the composition siding pressed against the inner wall 12 of the sections as previously described and then nailed directly to the sheathing.

10 I have thus provided a metallic moulding which may be used to trim the siding of a newly-built or reconditioned house, which moulding is economical to manufacture and of upkeep and which may be used as a universal moulding for any type of siding, insuring a water-tight sealed joint around the window or door opening.

15 While a preferred embodiment of the invention has been shown and described herein, it is obvious that additions, changes, and omissions may be made in the invention without departing from the spirit and scope thereof. For instance, changes in the shape and relative dimensions of the moulding sections may be made; the main feature of the invention residing 20 in the transverse resiliency or flexibility of the moulding sections which provides a spring-tight seal. The moulding sections may of course be used in other ways than those illustrated in Figs. 3 through 9, these specific applications 25 being presented by way of example only. While the moulding sections have been described as adapted to trim window and door openings, it is obvious that they may be used to trim or border any other type of opening in the outside or inside of a house.

30 I claim:

1. An article of manufacture formed of metal for use as a trim in finishing off siding installations around door, window and other openings 35 formed in a building, said article comprising a body portion having a pair of spaced, normally parallel walls, each of said walls having a pair of opposed side edges, each of said walls having their respective adjacent side edges joined 40 by an integral transverse wall, one of said walls having a greater width than the other of said walls, an integrally formed flange extending laterally from the other of said side edges of the other of said walls, said walls being bendable toward each other, and said body being sufficiently resilient to urge said walls away from each other to their normal position.

2. An article of manufacture formed of metal for use as a trim in finishing off siding installations around door, window and other openings 45 formed in a building, said article comprising a body portion having a pair of spaced, normally parallel walls, each of said walls having a pair of opposed side edges, each of said walls having their respective adjacent side edges joined by an integral, substantially U-shaped, transverse wall, one of said walls having a greater width than the other of said walls, an integrally formed flange extending laterally from the other of said side edges of the other of said walls, said walls being bendable toward each other, and said body being sufficiently resilient to urge said walls away from each other to their normal position.

3. An article of manufacture formed of metal for use as a trim in finishing off siding installations around door, window and other openings 50 formed in a building, said article comprising an elongated body portion having a pair of

spaced, normally parallel walls, each of said walls having a pair of opposed side edges, each of said walls having their respective adjacent side edges joined by an integral transverse wall, one of said walls having a greater width than the other of said walls, said one wall having a longitudinally extending groove formed therein adjacent said transverse wall, an integrally formed flange extending laterally from the other of said side edges of the other of said walls, said walls being bendable toward each other, and said body being sufficiently resilient to urge said walls away from each other to their normal position.

4. An article of manufacture formed of metal for use as a trim in finishing off siding installations around door, window and other openings formed in a building, that article comprising a body portion having a pair of spaced, normally parallel walls, each of said walls having a pair of opposed side edges, each of said walls having their respective adjacent side edges joined by an integral transverse wall, one of said walls having a greater width than the other of said walls, an integrally formed flange extending laterally from the other of said side edges of the other of said walls, said flange having an elongated, strengthening rib intermediate the sides thereof, said walls being bendable toward each other, and said body being sufficiently resilient to urge said walls away from each other to their normal position.

5. An article of manufacture formed of metal for use as a trim in finishing off siding instal-

lations around door, window and other openings formed in a building, said article comprising a body portion having a pair of spaced, normally parallel walls, each of said walls having a pair of opposed side edges, each of said walls having their respective adjacent side edges joined by an integral transverse wall, one of said walls having a greater width than the other of said walls, said one wall having a longitudinally extending groove formed therein adjacent said transverse wall, an integrally formed flange extending laterally from the other of said side edges of the other of said walls, said flange having an elongated, strengthening rib intermediate its sides, said walls being bendable toward each other, and said body being sufficiently resilient to urge said walls away from each other to their normal position.
